UNITED STATES PATENT OFFICE.

ISAAC COHN, OF BROOKLYN, NEW YORK, ASSIGNOR TO EYE BRAND CONFECTIONERY, INC., OF BROOKLYN, NEW YORK, A CORPORATION OF NEW YORK.

CANDY-MOLD.

1,303,773.

Specification of Letters Patent.

Patented May 13, 1919.

Application filed January 29, 1919. Serial No. 273,894.

To all whom it may concern:

Be it known that I, ISAAC COHN, a citizen of the United States, residing in the borough of Brooklyn, in the county of Kings and 5 State of New York, have invented certain new and useful Improvements in Candy-Molds; and I do hereby declare the following to be a full, clear, and exact description of the invention, such as will enable others 10 skilled in the art to which it appertains to make and use the same.

This invention relates to molds, and particularly to sectional molds for casting or forming blocks or pieces of rectilinear form, 15 although, obviously, the shape may be variously preferred.

Particularly the invention relates to the art of molding candy, and especially the hard candies, and in the accompanying disclosure the candy is referred to as being cast in rectilinear blocks of any size, and the invention therefore resides in the provision of a mold by which this type of candy can be 20 efficiently molded and easily removed from 25 the molds when it has hardened; one of the objects being to reduce or eliminate the percentage of waste product owing to fracture or breakage of the rectilinear blocks while being removed from molds of various well 30 known types.

It is another object of the present invention to provide a mold for facilitating the economical casting and removing of rectilinear blocks, which mold will be of simple, 35 practicable, substantial, durable and inexpensive character, and which may be operated or used in the process of casting the pieces by inexpert persons and yet will produce a maximum acceptable quantity of 40 product.

With this and such other objects in view as will be rendered manifest to those versed in the art, the invention consists in the construction, combination, and in details and 45 arrangements of the parts as are more particularly described in the following specification with relation to the embodiment of the invention described herein and illustrated in the accompanying drawings, in 50 which:

Figure 1 is a perspective view of the complete and assembled mold, showing the cast *in situ*;

Fig. 2 is a perspective view showing the 55 mode of separating the mold sections and

illustrating the adherence of certain of the blocks when the mold sections are separated;

Fig. 3 is a perspective view of the mold parts fully separated to clearly illustrate their construction.

In the illustrated embodiment of the invention the mold comprises a female section 2 and a male section 3, which may be made of any suitable material and in any suitable proportions and preferred configuration, as 60 determined by the shape and size of the cast to be produced. A particular feature of my present invention resides in the construction of this mold in such manner as to facilitate the separation of the mold sections 2 and 3, 65 with the object of reducing or eliminating wastage by the fracture or chipping or cracking of the casts, which in the present instance are shown in the form of rectilinear blocks; and in order to achieve this function 70 each of the mold sections 2 and 3, which are in the form of elongated, longitudinal side members, is provided with a series of transversely extending walls or partitions 4, here shown as being of a depth equal to the 75 height of the wall or mold section 2, while the opposite or companion section 3 is similarly provided with a series of transversely extending partitions or walls 5, equal in depth to the walls 4; but, as is clearly shown, 80 the walls 4 and the walls 5 are offset or staggered with relation to each other on their respective sections 2 and 3, the widths of the walls 4 and 5 being in the present illustration 85 equal to each other, so that the ends of the walls are designed to come into close juxtaposition to the adjacent surface of the opposite mold member or section when these parts are assembled. The result is that each 90 of the walls or partitions 4 and 5 forms an 95 inner end of an adjacent pocket when the mold is assembled as in Fig. 1, and therefore after the material has been poured and the cast has set or hardened, then by laterally separating the mold sections 2 and 3, 100 as clearly shown in Fig. 2, while certain of the casts or blocks of candy in the present adaptation and illustrated at B, may adhere to the contiguous walls and the pocket on one of the sections in which it might have 105 been cast, yet the block B can be readily removed without fracture or destruction because it is designed to have movement longitudinally of the mold section 2 or 3 as well as laterally from the mold section, for the 110

reason that each of the lugs 4 or 5 when the sections are separated leaves a space, as indicated at S, Fig. 2, between contiguous ends of a pair of blocks B when these adhere in 5 the positions shown in Fig. 2.

Any suitable means may be utilized to define the relative position of the mold sections 2 and 3, either extraneous or inherent to the molds, and in the present case I have 10 shown the ends of the section 2 as slightly rabbeted, as at 2', vertically on its inner end faces, while the end lugs or partitions 3' are slightly greater in length than the lengths 15 of the intermediate and staggered lugs or partitions 4-5, so that they will mortise into the rabbets 2', and these will serve to prevent the longitudinal movement of the sections one with respect to the other when 20 these are assembled, as for instance, upon the top plane surface of a bench or other support. It will be observed that these mold sections have neither tops nor bottoms for 25 the pockets, thereby giving free access to the upper and lower ends of those blocks of candy or other material which may be cast, which adhere to their adjacent seats on one or the other of the mold sections.

I claim:

30 1. A mold comprising a pair of longitudinal sections, means for coördinating the sections in respective operative position; and means arranged alternately on the pocket faces of the sections to form mold pockets between the sections, said means each forming one end wall of a pocket.

35 2. A mold comprising a pair of longitudinal sections, means for coördinating the sections in respective operative position; and

means arranged alternately on the pocket faces of the sections to form mold pockets 40 between the sections, said means each forming one end wall of a pocket, whereby when the sections are laterally separated the cast may be shifted endwise of the mold as well as laterally therefrom.

45 3. A mold comprising a pair of longitudinal sections each having on the pocket faces partitions staggered with respect to those of the other so that the portions form with their sections complementary L-shaped 50 pocket walls.

55 4. A mold comprising a pair of longitudinal mold sections, means for defining their casting position, and transverse partitions on the pocket faces of the sections the partitions being staggered with respect to each other so that when the sections are laterally separated the cast is free to be moved laterally or longitudinally from the section to which it may adhere.

60 5. A mold comprising a pair of longitudinal, laterally separable sections each having transverse partitions which are relatively staggered on the sections so that each partition forms the end of an adjacent 65 pocket when the sections are assembled.

65 6. A mold comprising a pair of longitudinal, laterally separable sections each having transverse partitions of equal length 70 which are relatively staggered on the sections so that each partition forms the end of an adjacent pocket when the sections are assembled.

In testimony whereof I affix my signature.

ISAAC COHN.
